UNITED STATES PATENT OFFICE.

ARTHUR J. BACKER, OF SYRACUSE, NEW YORK.

RAILWAY-SWITCH AND OPERATING MEANS THEREFOR.

SPECIFICATION forming part of Letters Patent No. 741,571, dated October 13, 1903.

Application filed February 9, 1903. Serial No. 142,485. (No model.)

To all whom it may concern:

Be it known that I, ARTHUR J. BACKER, of Syracuse, in the county of Onondaga, in the State of New York, have invented new and useful Improvements in Railway-Switches and Operating Means Therefor, of which the following, taken in connection with the accompanying drawings, is a full, clear, and exact description.

10 This invention relates to improvements in electrically-operated railway-switches in which the switch-point is automatically thrown to the desired position by electrically-operated means through which the circuit is closed by a suitable device provided on the car under the control of the operator, whereby the switch may be readily shifted by an approaching car without stopping said car.

15 The object of this invention is to enable the motorman to throw the switch by means of an electrical device operated by the power current without leaving or stopping the car, thereby saving time and insuring the operation of the switch at night, when it would be impossible to locate the position of the switch until the car was in close proximity thereto.

20 Another object is to inclose the switch-operating device within the switch-point, so that the same is concealed and protected from the elements.

25 Referring to the drawings, Figure 1 is a diagrammatic view of a main track and a turnout of a railway system, showing the trolley-wire and the means for diverting the current to the switch-operating device. Fig. 2 is an enlarged top plan, partly in section, of the switch-point and its operating mechanism. Figs. 3 and 4 are sectional views taken, respectively, on lines 3-3 and 4-4, Fig. 2.

30 Similar reference characters indicate corresponding parts in all the views.

In the drawings, 1 represents a main track, and 2 a turnout from the main track, and 3 is a movable switch-point normally connected in the main track and supported on a frog 4. Arranged in close proximity to the outer rail of the frog 4 is a conductor or additional rail 5, which is preferably arranged parallel with and in proximity to the outer rail of the turnout and extends a consider-

able distance beyond the opposite ends of the switch for a purpose hereinafter described.

The switch point 3 is mechanically held in one or the other of its extreme positions and is here shown, Fig. 1, as normally opened for the direct track and is adapted to be thrown to the opposite position by electrically-operated means, presently described, when the motorman desires to switch the car onto the turnout. This switch-point is pivotally mounted at one end upon the frog 4, which frog is provided with an upwardly-projecting stud or bearing 6, and the switch is provided with a hub 7, projecting upwardly from its lower wall 8 and encircles the stud 6, suitable ball-bearings 9 being provided at the upper and lower ends of the stud and hub for permitting the easy swinging action of the switch-point, said hub being secured to the switch by laterally-projecting arms 10.

70 The pivoted end of the switch-point is provided with an inner chamber 11, which is entirely inclosed on all sides, the upper wall being provided with an opening 12, which is normally closed by a removable plate or cap 13, the purpose of this plate being to permit access to the chamber 11. Mounted within this chamber 11 is a pair of electromagnets 14, which are secured to a block 15 of insulating material, and this block 15 is in turn secured 80 to one end of a fixed arm or bracket 16. The other end of the bracket 16 is secured to the fixed upright stud or bearing 6 and preferably extends through a slot 17 and is provided with an extension 18, to which is attached one end of a spring 19, the other end of said spring being secured to one of the side walls of the switch-point. The spring 19 is the mechanical means for holding the switch-point in its normal position, as seen in Fig. 1, 85 so that the car will always take the main track unless the switch-point is thrown to the other position by the electromagnets 14.

90 It is evident from the foregoing description and Figs. 2 and 3 of the drawings that the electromagnets are fixed from movement at one side of the pivotal bearing or stud 6 and constitute the electrical means for moving the switch-point in one direction, while the spring-motor 19 is connected to the fixed extension 100

18 and to the heel of the switch-point at the opposite side of the stud or bearing 6 and constitutes the mechanical means for throwing the switch-point in the opposite direction, 5 yieldingly holding it in this position.

In order to permit the rocking movement of the hub 7 relatively to the bracket 16, said hub is provided with slots or cut-outs 21 in its front and rear walls for receiving the fixed 10 bracket or arm 16, these slots or cut-outs being of sufficient circumferential length to permit the free movement of the switch-point to its extreme opposite positions without friction between the hub and the bracket.

15 One end of the coil of the electromagnets 14 is electrically connected by the wire 22 to a conductor or outside rail 5, the other end of said coil being grounded through the medium of a wire 23, which is here shown as connected to the switch-point, it being understood that said switch-point is of conducting material, such as cast or wrought iron, and that the rails of which the switch-point forms a part are grounded in the usual manner for 20 electric-railway systems.

I have thus far described the switch-point and the electrical and mechanical means for controlling its action, and I will now proceed to describe the means for controlling the flow 25 of the electric current through the conductor 22 and magnets 14. This means preferably consists of a contact member, such as a brush 24, which is mounted upon the car and is adapted to be forced into electrical contact 30 with the conductor 5 when the car is approaching the switch and it is desired to take the siding or turnout. This contact member is electrically connected by a conductor 25 to the trolley-wire 26 through the medium of 35 the trolley-pole 27, which is shown diagrammatically in Fig. 1, a suitable electric switch or circuit-breaker 28 being placed in the connection between the contact member and trolley-pole, so that the circuit through the 40 contact member may be broken when desired.

The operation of the contact device is controlled manually by the motorman or other attendant and is here shown as mounted upon one end of a bell-crank lever 30, to which is 45 connected a foot-pedal 31, whereby the contact member 24 may be forced into contact with the conductor 5 by simply depressing the foot-pedal 31 against the action of a spring 32, said spring serving to return and to hold 50 the contact member in its normal position.

In order to prevent the accumulation of dirt, snow, or other refuse in the path of the switch-point, I provide the side walls of the frog upon which the switch-point is mounted 55 with opening 33 and vertical bars 34, which bars are pointed or V-shaped at their inner edges to facilitate the passage of the debris through the opening 33.

In the operation of my invention suppose 60 the car to be moving in the direction indicated by arrow *x*, Fig. 1, toward the switch-point and it is desired to switch the car from

the main track onto the turnout, then as the car approaches the switch the motorman depresses the pedal 31 against the action of the spring 32, and thereby forces the contact-brush 24 into a position to contact with the conductor 5, which is in electrical connection with the magnets 14. As soon as the contact takes place, which it does considerably in advance of the point of the switch, the circuit is closed from the trolley-wire through the conductors 27, 25, 5, and 22, through the magnets, and thence to the ground through the medium of the conductor 23 and the rails. 75 This energizes the magnet 14, which attracts an armature forming a part of one of the side walls of the chamber 11, and therefore rocks the switch-point in the direction indicated by arrow *y*, Fig. 2, to throw the switch-point to 80 its other extreme position away from the outer rail of the side track, which permits the car to readily run on the siding or turnout, it being understood that the conductor 5 is of sufficient length to permit the rear 90 wheels of the car to pass the switch-point before the brush 24 leaves the advance end of the conductor 5, the object of this being to maintain the current through the magnets until all the wheels of the vehicle have passed 95 over beyond the switch-point, and as soon as this is accomplished the brush leaves the conductor 5 and is returned to its normal position by the spring 32, thereby breaking the circuit through the magnets and permitting 100 the motor 19 to return the switch-point to its normal position.

Having thus described my invention, what I claim, and desire to secure by Letters Patent, is—

1. In combination with a railway switch-point having a chamber therein, an electric circuit, an electric switch-point-operating device located in the chamber and connected in said circuit, and means to close the circuit through said device.

2. In combination with a railway switch-point having a chamber therein, an electric circuit, an electric switch-point-operating device located in the chamber and connected in 115 said circuit, an exposed electric conductor in electric connection with said device, and means on the car to close the circuit through the conductor for the purpose described.

3. The combination with a railway switch-point and electric circuit, of an exposed electric conductor, an electric switch-point-operating device located within the switch-point and electrically connected to said conductor, a contact device on the car connected in the 125 circuit, and means to contact said contact device with the exposed conductor to close the circuit through the switch-point-operating device for the purpose set forth.

4. In combination with a railway switch-point, means to close the switch-point in one position, an electric circuit including electrically-operated means located in the switch-point to throw it to its other position, an ex-

posed conductor in the circuit and electrically connected to the electric switch-point-operating means, and a manually-operated device on the car to close the circuit through the exposed conductor.

5. In combination with a railway switch-point pivotally mounted at one end, and provided with an interior chamber, an electric circuit, an electromagnet located in the chamber and operating to throw the switch-point in one direction, mechanical means to throw the switch-point in the opposite direction, an electric conductor connected in circuit with the magnet, and a contact device on the car 15 for closing the circuit through the conductor and magnet.

6. In combination with a support having a fixed stud or bearing, a railway switch-point

journalized on the bearing and provided with an internal chamber and an opening through 20 one of the walls of the chamber, a closure for the opening, an electric circuit including therein an electromagnet located in the chamber and fixedly connected to said bearing to throw the switch-point, a conductor electrically connected to said magnet, a contact device in the circuit and carried by the car, and manual means for contacting said device with the conductor to close the circuit through the magnet for the purpose set forth. 25

In witness whereof I have hereunto set my hand this 30th day of January, 1903.

ARTHUR J. BACKER.
